PILL DISPENSER

Conrad Cage, Jr., 107 Linderman Ave., West Monroe, La.
Filed Nov. 21, 1962, Ser. No. 239,179
8 Claims. (Cl. 206—42)

This invention relates to pill dispensers. More specifically this invention relates to a pill dispenser having a plurality of compartments and indicia receiving means adjacent each compartment.

Frequently, patients suffering from various disorders are given a prescription requiring dosages of pills, capsules or liquid medicines at certain prescribed times, for instance every hour or after each meal. When such a schedule as is to be followed for any length of time it frequently happens that at the time prescribed for the dosage the patient may be distracted. After the distraction has passed the patient may have difficulty in recalling whether or not the appropriate dosage has been taken. This uncertainty may result in the patient either taking a double dosage or none at all, and either eventuality can be quite serious insofar as many pills and illnesses are concerned.

It also frequently happens that two or more pills or capsules of different types are prescribed to be taken at the same time. The presence of a plurality of containers can often be a source of confusion and such uncertainty may also result in the patient either taking a double dosage or none at all.

Thus it is a primary object of this invention to obviate these problems and dangers by providing a pill dispenser having a plurality of separate compartments, each being large enough to receive several pills or capsules and having indicia means associated with each compartment, so that the times prescribed for the dose may be visually compared and checked with the presence of pills or capsules in the compartment. In this manner the possibility of double doses or overlooked doses can be entirely eliminated.

Another object of this invention is to provide a pill dispenser which is particularly adapted for use in the patient's home or in hospitals and convalescent homes.

Another object of this invention is to provide a device which will protect pills or capsules from moisture or soiling and thereby provide maximum protection for the medicinal value of each dose. This object is further enhanced by decreasing to a minimum the manipulation incident to the dispensing of pills and capsules.

A further object of this invention is the provision of a pill dispenser which may be simply and economically constructed and yet will be durable and attractive.

Other advantages and objects will become readily apparent from a consideration of the following description taken in conjunction with the appended drawings which illustrate one embodiment of my invention.

In the drawings:

FIGURE 1 is a front view of a pill container section according to this invention;

FIGURE 2 is a side view of FIGURE 1;

FIGURE 3 is a perspective view of a complete pill dispensing unit in accordance with this invention;

FIGURE 4 is a cross sectional view along 4—4 of FIGURE 1;

FIGURE 5 is a cross sectional view similar to FIGURE 6, but with a slotted sleeve;

FIGURE 6 is a cross sectional view along 6—6 of FIGURE 3;

FIGURE 7 is a cross sectional view along 7—7 of FIGURE 8;

FIGURE 8 is a side view of another embodiment of this invention;

2

FIG. 9 is a front view of one embodiment of the sleeve in accordance with this invention.

In its broadest sense the present invention comprises:

- (a) A tubular member having a plurality of compartments spaced at intervals along the length thereof,
- (b) An opening into each of said compartments through the side walls of said tubular member,
- (c) Changeable indicia means located adjacent to each of said compartments,
- (d) A sleeve member slidable with respect to the external surface of said tubular member,
- (e) A supporting means at one end of said tubular member.

Referring now to the drawings it will be seen that the tubular member 12 is divided into a plurality of separate compartments A, B, C and D by means of a plurality of partitions 14a-14e extending perpendicularly to the axis of the tubular member 12 at spaced intervals. Although the tubular member 12 has been shown as having a generally cylindrical cross section it will be understood that it could just as well be in a form having the cross section of a square, triangle, rectangle or even a polygon. A cylindrical cross section is desirable from the standpoint of economy and ease of manufacture since it involves a simple extrusion operation. Obviously any number of compartments could be provided.

The partitions 14a-14e may be fixed within the tubular member 12 at the desired locations by any suitable fastening means such as adhesives, locking projections or the like.

It will be further noted in the drawings that one side of the tubular member 12 has an elongated open slot 38 therein which allows access to each of the compartments, A, B, C and D, formed by said partition members and which (preferably) restricts discharge of pills from the compartment. The width of this slot 38 is preferably less than the internal diameter of the tubular member 12 and may be just wide enough to accommodate the smallest dimension of a pill or capsule placed in the compartments A-D.

Each of the various compartments is of a sufficient size to receive at least one pill and preferably several pills or capsules. For example, a compartment size of one inch in length (height) by $\frac{3}{4}$ inch in diameter has been found to be quite suitable.

FIGURE 2 most clearly shows the changeable indicia means. By way of example this is shown to consist of abraded portions 30, 32, 34 and 36 located at spaced intervals along the exterior side of the tubular member 12. These abraded portions may be marked on with a crayon-type pencil, a lead pencil, ink or the like. Each of these abraded portions is positioned so as to be unmistakably associated with one of the compartments (A-D) of the container. The appropriate time for taking the pills in the adjacent compartment is indicated on each abraded portion. The written indicia can be erased or changed whenever desired by the patient or attending physician. The abraded portion (or other indicia) should preferably be recessed somewhat to prevent the writing thereon from being obliterated by relative movement between the tubular member 12 and the sleeve which is more fully described hereinafter.

At the upper end of the dispenser a shank 22 is provided which includes a hole 24. This arrangement permits the dispenser to be suspended from a hook or attached with a string to a hospital bed or other convenient location near the patient utilizing the dispenser.

After pills, capsules and/or instructions have been placed in the various compartments with an indication of the appropriate time for use being indicated on the adjacent abraded portion, a sleeve member is placed around the tubular member. Referring specifically to

FIGURES 3, 5, and 6, a sleeve member 26 is shown being disposed around the tubular member 12. The sleeve member effectively closes each of the compartments and prevents contamination thereof by dust, dirt, etc. The internal diameter of the sleeve member 26 is preferably chosen so that a frictional fit is achieved between the outside of the tubular member 12 and the inside of the sleeve member 26. In other words, the sleeve members 26 will freely slide with respect to tubular member 12 upon the application of manual pressure but otherwise will stay in position.

The sleeve member 26 may be a continuous cylinder as indicated in FIGURE 6 or it may have a rather narrow slot 28 running the axial length thereof (FIGURE 5). The advantage of an axial slot in the sleeve 26 is that it permits one to use the natural resilience of the sleeve material to provide a frictional grip on the exterior of the tubular member 12. Also, if the slot 28 is made approximately the same width as the slot 38, then slot 28 can be used as a sort of gate to open and close slot 38. The advantage of a transparent sleeve is apparent when immediate access to the data on the abraded portion is desired.

Since the sleeve member 26 can be moved rather easily in an axial direction with respect to the tubular member 12 by the application of manual pressure it will be seen that in so doing one progressively exposes the compartments A, B, C and D and the indicia means adjacent each compartment.

The lower end of sleeve 26 may also be provided with an annular metallic band around its interior surface so as to provide for continued retention of the resilience necessary for frictional contact.

Still another variation of a suitable sleeve member is shown in FIGURE 9. Here it is seen that the sleeve 26 is provided with axially staggered openings 61, 62, 63 and 64 which can be caused to sequentially register one at a time with the various compartments A, B, C, and D in the tubular member 12 by rotating the sleeve member 26 and the tubular member 12. With this arrangement, if the tubular sleeve 26 is made of clear plastic, it need never be moved axially with respect to the tubular member 12 in order to discharge dosages.

FIGURES 7 and 8 illustrate another embodiment of the invention relative to the changeable indicia means. In this embodiment, instead of using abraded portions of the exterior wall of tubular member 12 for the indicia means, a wedge shaped slot 51 and indicia strip are employed. The indicia strip 50 desirably already has pre-printed times thereon. This would permit a druggist, at the time he sold a patient medicine to also supply the patient with a dispenser having the appropriate number of compartments and an appropriate indicia strip 50 for insertion in the slot 51. The druggist could easily have available a variety of different preprinted indicia strips already.

This invention will be seen to be very advantageous to patients who have to take a series of dosages at intervals. The time for taking each dosage is simply written on the abraded portions 30, 32, and 36 with a pencil or other writing instrument end each of the compartments filled with pills. The dispenser is preferably filled at the same time each day, either in the morning or before retiring. In the event that dosages of pills are to be alternated with liquid medicinal dosages a small slip of paper indicating the composition or location of the liquid dosage can be placed in the appropriate compartment. Of course, each of the compartments may be filled with both slips of paper and pills. This arrangement avoids doubt in the patient's mind as to whether the prescribed dosage has been taken at the scheduled time, for whenever a pill still remains in a compartment beyond the time set forth on the indicia means the patient will know that the pill has not been taken.

In its preferred mode of operation the sleeve 26 is

moved relative to tubular member 12 so as to first expose compartment A and lastly compartment D.

Between dosages the container may be suspended or otherwise immediately placed near the patient.

The various parts of the dispenser may be formed of any suitable material. Plastic such as polyethylene, polystyrene, etc. are quite satisfactory and economical and clear, transparent plastic is especially preferred.

In conclusion, while I have illustrated and described some preferred embodiments of my invention, it is to be understood that since the various details of construction may obviously be varied considerably without really departing from the basic principles and teachings of this invention, I do not limit myself to the precise constructions herein disclosed and the right is specifically reserved to encompass all changes and modifications coming within the scope of the invention as defined in the appended claims. Having thus described my invention, what I claim as new and desire to secure a United States Letters Patent for is:

1. A pill dispenser and reminder comprising:
  - (a) an elongated tubular member;
  - (b) a plurality of partitions equal in diameter to the internal diameter of said tubular member mounted perpendicular to the axis of said tubular member and adapted to close the top and bottom and divide said tubular member into a plurality of laterally-disposed compartments for receiving pills;
  - (c) said tubular member having formed in its side wall openings opposite each of said compartments, said openings having an arcuate dimension of less than 180° and being vertically aligned one above the other to permit insertion of and removal of pills from said compartments;
  - (d) indicia receiving means formed on the outer wall of said tubular member opposite each of said compartments and adapted to temporarily receive visible reminders of times to consume the contents of each of said compartments; and
  - (e) transparent sleeve means frictionally engaging the outer surface of said tubular member and adapted to alternately close all of said compartment openings and open a selected one of said openings.
2. A dispenser in accordance with claim 1 wherein the openings in the wall of the tubular member are formed as a longitudinal slot in the wall of said tubular member parallel to the axis thereof.
3. A dispenser in accordance with claim 1 wherein the indicia receiving means is a roughened surface formed on the outer wall of the tubular member and adapted to be marked on by an erasable marking means.
4. A dispenser in accordance with claim 1 wherein the indicia receiving means is a longitudinal groove formed in the outer wall of the tubular member and adapted to receive a strip member appropriately marked with visible reminders.
5. A dispenser in accordance with claim 1 wherein the sleeve member is longitudinally slideable on the tubular member to sequentially expose that opening of the compartment immediately adjacent the previously exposed opening.
6. A dispenser in accordance with claim 1 wherein the sleeve member is longitudinally fixed with relation to the tubular member and adapted to rotate about said tubular member and additionally has formed in its wall a plurality of openings equal in number to the number of compartments, spaced along said sleeve opposite said compartments and at different angular positions, and adapted to register with a different one of the openings in the compartments as the sleeve is rotated about the tubular member.
7. A dispenser in accordance with claim 1 which additionally includes a vertical tab formed on the upper end of the tubular member and having a hole therethrough to accommodate a suspending element.

8. A dispenser in accordance with claim 3 wherein the roughened surface is formed in a recess in the wall of the tubular member.
